UNITED STATES PATENT OFFICE.

CHARLES L. DE MARTIN, OF CONNERSVILLE, INDIANA, ASSIGNOR TO INDIANA LAMP COMPANY, OF CONNERSVILLE, INDIANA, A CORPORATION.

LAMP-DOOR CONSTRUCTION.

1,369,732.

Specification of Letters Patent. Patented Feb. 22, 1921.

Application filed June 2, 1919. Serial No. 301,222.

To all whom it may concern:

Be it known that I, CHARLES L. DE MARTIN, a citizen of the United States, and a resident of Connersville, county of Fayette, and State of Indiana, have invented a certain new and useful Lamp-Door Construction; and I do hereby declare that the following is a full, clear, and exact description thereof, reference being had to the accompanying drawings, in which like numerals refer to like parts.

This invention relates to the construction of the rim for a headlight door or lamp so as to give it the appearance of a solid and massive metal rim, whereas, in fact it is formed entirely from a stamping process of sheet metal. This is accomplished by means of stamping out two shells, embodying one stamping operation each, mounting them together, and joining them to form a single rim.

Referring to the drawings, which are made a part of this application, Figure 1 is a front elevation of the lamp door. Fig. 2 is a side elevation with the upper portion shown in section. Fig. 3 shows a section through the stamping of the outer shell. Fig. 4 shows a section through the stamping of the inner shell. Fig. 5 shows a section through the two stampings assembled to form the door rim.

In the drawing there is shown a lamp door rim having an outer octagonal shell 10 with an inner circular bead 11 formed therein, for the purpose of engaging and setting off the lens. The outer shell is formed by a single stamping process by means of a die in which the sheet metal is stamped so as to draw up the side wall 12, its periphery being octagonal, and form beads 11 about the inner periphery thereof.

The inner shell is formed of sheet metal in a die which draws the wall 13 upwardly,

its periphery being circular and provided with a lateral flange 14, which has its periphery octagonal so as to correspond to the octagonal shape formed in the wall 12. The inner portion of said inner shell is stamped in the same operation to provide a laterally extending rim 16, with a downwardly projecting flange 17, and with a plurality of ears 18 sheared from the rim 16 and turned upwardly to form a supporting and retaining means for the lens to be secured in said door.

Before assembling the shells the inner shell has a recess 19 stamped out whereby said lamp door may be mounted and secured to the casing by means of hooks extending therethrough.

After the shells have been stamped and formed they are assembled as shown in Figs. 2 and 5, being secured together by a spot welding process at intervals 20 to the inner rim, and soldered at the joint 21 to the inner periphery.

The invention claimed is:

A sheet metal door for lamps having a circular inner rim and a non-circular outer periphery, consisting of an outer member 70 having the wall thereof of a non-circular shape, an inner shell having the wall thereof of circular shape and having a lateral portion of non-circular shape to coincide with the non-circular wall of the outer shell, 75 whereby the edges thereof may register with each other, means for securing the edges of said shell together whereby the sheet metal door comprised of two shells will give the appearance of a solid non-circular shaped 80 door rim, and means integral with the inner shell for securing a closure member within the outer shell.

In witness whereof, I have hereunto affixed my signature.

CHARLES L. DE MARTIN.
